DEVELOPER

Clarence O. McMaster, St. Paul, Minn., assignor to Minnesota Mining and Manufacturing Company, St. Paul, Minn., a corporation of Delaware
No. Drawing. Filed Oct. 17, 1958, Ser. No. 767,787
12 Claims. (Cl. 204—18)

This invention relates to the formation of permanent visible reproductions of light-images on photoconductive surfaces by methods involving electrolysis at the exposed light-sensitive surface. It has particular reference to improve electrolytic developer solutions employed in such method.

Methods have recently been devised for electrolytically forming visible reproductions of light-images on strongly photoconductive light-sensitive copy-sheet materials. Apparatus for carrying out such methods, particularly in making enlarged reproductions of microfilm copies of graphic originals, has also been made available. Typically, there is involved the brief irradiation of a sensitive copy-paper with a light-image corresponding to the copy desired, and the subsequent electrodeposition at the conductive light-struck areas of a metallic image-forming material as the copy-paper is withdrawn from the irradiation area. The copy is obtained in substantially dry form, since only a surface application of developer solution is applied. No subsequent treatment, such as heating, washing, or subjecting to the action of chemical vapors, is required. Completed reproductions of microfilm transparencies or other graphic originals may be produced at a rate of ten or more per minute.

A recommended form of light-sensitive copy-paper for use with the apparatus and method hereinabove identified consists of a strongly photoconductive zinc oxide surface coating on a metallized or metallic conductive backing or sheet material. Such a sheet, having an 0.8 mil coating of four parts by weight of zinc oxide, and one part of polymeric insulating binder on a laminate of paper and thin aluminum foil, typically has a conductivity value measured as hereinafter described of at least about 10^{-7} mho/cm. and preferably not less than about 10^{-6} mho/cm. Under equilibrium dark conditions the conductivity value is not higher than about one-twentieth of the conductivity value under illumination, and ordinarily is much lower.

The conductivity value is measured as follows: A small sample of the sheet material is insulated at back and edge areas with a nonconductive waterproof covering, e.g., of plastic adhesive tape, an electrical connection to the conductive metallic substrate being provided. The sample is suspended in a transparent glass cell containing 200 ml. of a solution of tenth-molar ammonium sulfate and facing an open frame electrode serving as the anode. Current flow per unit area through the measured thickness of the coating under an applied voltage is measured both with the sample under equilibrium dark conditions and when illuminated. A potential of 10 volts is convenient but not critical. Values at several thicknesses of coatings may be determined and the value at a standard thickness of 0.8 mil obtained by interpolation. Illumination is provided from a 500 watt incandescent-filament lamp, i.e., at an intensity of about 1300 foot-candles. The photoconductivity value is calculated from the values thus obtained.

As electrolytic developer solutions for use in the above-identified apparatus and method, there have been suggested solutions of salts of platable metals, e.g. copper sulfate, nickel chloride, or cadmium nitrate solutions. An initially visible image may indeed be formed with each of these; but for one reason or another the resulting copy has not been entirely satisfactory. For example, with

2

platable base metals the image is found to fade rapidly when the copy is exposed to high humidity. Since some moisture is unavoidably present at the surface of the sheet following image development, it is seen that conditions are normally unfavorable for image permanency. Furthermore, although electrolysis of many such salts does initially produce a visible image, the quality of the image is low. The image areas obtained are in most cases grayish rather than the desired dense black, and the copy lacks contrast. The noble metals produce no better, or even less effective images. Silver nitrate, for example, produces a yellowish-brown image and a darkened background. Gold salts likewise produce images of low density. Solutions of gold and platinum are highly corrosive to metallic structural components and prohibitively expensive for most copying purposes.

In all cases it will be appreciated that the residual unreacted salts, or residues resulting from the electrolytic decomposition of such salts, remain on or dispersed within the surface of the coated sheet. It is suggested that the reaction of such materials with the extremely thin metallic deposits forming the image areas is responsible, in the case of the base metals and in the presence of sufficient moisture, for the rapid re-dissolving of the deposited material and fading of the image. In some instances, traces of additional reactive salts or other materials obtained from the copy-sheet itself or from other sources, may increase the rate or extent of dissolution and disappearance of the image. In any event, and regardless of theory, it has been experimentally shown that image areas formed by electrolysis of salts of platable base metals under the conditions hereinbefore described more or less rapidly disappear when the sheet is held in a moist atmosphere.

The present invention provides electrolytic developer solutions useful, in the processes and apparatus hereinbefore identified, for the preparation on photoconductive zinc oxide coated copy-paper or other equivalent sensitized sheet material, of long-lasting images of high density and contrast. The solutions do not rapidly deteriorate under conditions experienced either in original containers during storage or in the copy-machine during continuous or intermittent use thereof, and are quite inexpensive. The image areas formed are in most instances a dense black in appearance, providing excellent contrast with the white background of the zinc oxide coating; and they are surprisingly resistant to fading under conditions of high average humidity.

Surprisingly, these and other advantages are attained, in accordance with the present invention, by combining with a solution of soluble salt of a platable base metal, such for example as cadmium nitrate, copper sulfate or nickel chloride, from trace amounts up to not more than minor amounts of a salt of a noble metal, as will now be more particularly pointed out in the form of illustrative but non-limitative examples.

Example 1

Ten parts by weight of hydrated nickel acetate ($\text{Ni}(\text{C}_2\text{H}_3\text{O}_2)_2 \cdot 4\text{H}_2\text{O}$) and 0.5 part of silver nitrate were dissolved in sufficient water to make 100 parts. The solution was placed in the reservoir of an electrolytic printing device, from whence it was applied to the exposed surface of the copy-paper by means of a narrow strip of cellulosic sponge dipping into the solution. The reservoir was connected through a source of potential to the conductive backing of the copy-paper. The copy-paper thus formed a cathode of an electrolytic cell, the metal reservoir being the anode. The oxide-coated surface of the paper was first exposed to a light-image for a few seconds, and the exposed surface then drawn slowly over the lightly contacting sponge. The light-struck areas immediately dark-

ened, changing to a dense black; the background areas remained white. The thin coating of solution remaining on the sheet was not apparent as a liquid layer and the water content was soon volatilized and removed.

A portion of the sheet having an average image density at an image area somewhat greater than $\frac{1}{4} \times \frac{1}{4}$ inch was tested for light-reflectance as compared with the unexposed copy-paper, by means of a "Densichron" optical density measuring instrument. Such an instrument measures the percentage of incident light reflected from a test surface in comparison with that reflected from a standard surface. With the instrument set to give a zero percent absorption reading (i.e. 100% reflection) for the unexposed sheet, a reading of 69 units was obtained from the image area, meaning that 69% of the light normally reflected from the unprinted copy-paper was absorbed. It may be shown that readings down to about 40-50 units in the image areas and 0-10 units (i.e., 90-100% reflection) in the background areas indicate highly acceptable graphic representations. Total absorption would be equivalent to 100 units on the scale indicated.

The print was stored for one week in a humidity chamber at room temperature and 98% relative humidity. The image density remained at 69 units. The background area likewise remained well below 10 units. Since this was found to be generally true in each of the examples, background values will not be reported hereinafter other than for exceptional cases.

Reducing the concentration of hydrated nickel acetate to 2% while maintaining the silver nitrate at 0.5% produced image areas of 63 unit initial density and showing no decrease on one week aging at 98% R.H.

In a comparative test, a solution of ten parts of the hydrated nickel acetate in water to make 100 parts, but in the absence of the silver nitrate, formed an image having an initial density of only 48 units. After one week at 98% R.H. the density had fallen to 41 units.

In another comparative test, a 0.5% solution of silver nitrate formed a yellowish brown image having a density of 40 units. After one week at 98% R.H. the reading was 44 units. Substantially identical results were obtained using concentrations of one and two percent of silver nitrate in water. At higher concentrations, e.g. at 10% of silver nitrate, visual inspection indicated no increase, and possibly a slight decrease in density as compared with that obtained in the neighborhood of one percent. The background areas were significantly darkened where the silver nitrate was the only salt present.

Example 2

A solution of three parts by weight of hydrated cadmium nitrate ($\text{Cd}(\text{NO}_3)_2 \cdot 4\text{H}_2\text{O}$), one-half part of tartar emetic

(antimony potassium tartrate, $\text{K}(\text{SbO})\text{C}_4\text{H}_4\text{O}_6 \cdot \frac{1}{2}\text{H}_2\text{O}$) and one-half part of silver nitrate in water sufficient to make 100 parts was employed as described under Example 1 in the electrolytic development of images. Dense black image areas were produced. The image areas did not observably decrease in density on storage for more than one week at 98% R.H. and normal room temperature.

A solution of 2% hydrated cadmium nitrate and 1% tartar emetic produced an initial density of 72 units, dropping to 60 units in a first week at 98% R.H. and to less than 50 units in a second week at the high humidity. The addition of 0.5% silver nitrate increased the initial density obtained to 82 units, and after one week in the test chamber the reading remained at 80 units.

Image areas produced with a solution of 2% of the hydrated cadmium nitrate were initially black but disappeared completely within about one hour at 98% R.H.

Initially black images produced with a 5% solution of tartar emetic disappeared within one week at 98% R.H. Density readings taken on the image areas were 42 units as

first developed, dropping to zero during the week of aging. The addition of 1% silver nitrate to this solution resulted in image areas having an initial density of 72 units, dropping to 66 units after one week in the test chamber.

Example 3

Solutions at 3% and at 10% concentrations of nickel nitrate in water produced no visible image when tested in the electrolytic development procedure as described in Example 1. The addition of small proportions of silver nitrate to the 10% solution resulted in formation of dense black images having an initial density, as measured on the "Densichron" instrument, of 73 units. After one week at 98% R.H. the density reading was 73 units.

Example 4

A solution of zinc nitrate at 3% concentration when applied to the electrolytic development process produced a dense black image which disappeared within a few seconds. Silver nitrate was added to the solution at a concentration of 0.5%. Images produced with this solution had an initial density of well over 69 units, and showed no observable diminution in one week at 98% R.H.

Example 5

Ten percent of hydrated magnesium nitrate and 5% of tartar emetic gave an electrolytic developer solution with which image areas were produced having an initial density of 61 units and a density after one week in the test cell of 44 units. The addition of 1% of silver nitrate increased the initial density to 69 units, and this value was retained in the aging test.

Example 6

A solution of 2% nickel acetate hydrate and 0.5% silver acetate produced an image area of 69 unit initial density; after one week in the test cell the density was 64 units.

Example 7

A solution of 2% nickel sulfate and 0.5% silver sulfate similarly provided an initial density of 72 units; after one week in the test cell the density was 67 units.

Example 8

A 0.5 percent concentration of ($\text{HAuCl}_4 \cdot 3\text{H}_2\text{O}$) when applied as an electrolytic developer produced an image having an initial density of 37 units. A 2.0% solution of antimony fluoride (SbF_3) similarly provided an image density of 37 units. A mixture of the two solutions produced an image area having a density of 56 units, and the high density level was permanently retained.

Electrolytic development is found to proceed at a more rapid rate with the mixed salt developers including silver ion or the like than in the absence of such material, as well as with the formation of improved images; and the mixed solutions also require somewhat less intensity or time of illumination of the copy-sheet with the light-image.

Although the proportion of silver salt may be varied considerably, and although extremely small trace amounts have produced an observable effect, it is generally found desirable to include at least about 0.01% by weight and in no case greater than about 5%. Excellent prints are obtained with concentrations in the neighborhood of 0.5 percent. Similarly, the concentration of the base metal salt may vary from as low as 1% or even somewhat lower up to 10% or 15% or somewhat higher. At too low a concentration the amount of metal ion is insufficient to produce the required density of image; at excessive concentrations, the amount of salts deposited on the copy-paper may be so high as to cause darkening of background areas. Excessive proportions of noble metal ion are economically undesirable and tend to cause deposition of such metal at background areas. Ordinarily the amount of silver ion or the like is therefore from trace amounts up to not more

than a minor proportion, in terms of molar ratio, of the total amount of platable metal ion.

Even trace amounts of silver ion are difficult to obtain in the case of difficultly soluble silver salts. In such cases it has been found helpful to add sodium thiosulfate in amount sufficient to dissolve an adequate amount of the silver salt.

Although images may be produced with solutions containing soluble salts of any of the metals below magnesium in the electromotive series when properly handled, it is found that salts of cadmium, nickel, zinc, copper and cobalt are in general most satisfactory. Among the remainder, ferric ion is undesirable since it is unstable when exposed to sunlight; and ferrous ion is incompatible with silver ion, causing reduction of the latter and deposition of metallic silver. Systems which are unstable on exposure to light or because of inter-reaction in this way are undesirable and are excluded.

Aqueous systems have been illustrated in the specific examples and are preferred; but ionizing solvents other than water are also useful. Solutions have, for example, been prepared in ethyl alcohol. Glycerine and formamide are also effective, but since they are essentially non-volatile they must subsequently remain on or in the sheet and their use is therefore not recommended.

What is claimed is as follows:

1. The process of producing long-lasting dense image-forming deposits on light-exposed areas of strongly photoconductive photosensitive copy-paper having a photoconductive coating on an electrically conductive backing, said copy-paper being capable of electrolytic image reproduction thereon, which comprises electrolyzing at the conductive light-exposed areas a stable liquid electrolytic developer solution consisting essentially of, in solution in an ionizing solvent, from about 0.1 to about 5 weight percent of a silver salt and from about 1 to about 15 weight percent of a soluble salt of a platable metal selected from the group consisting of cadmium, nickel, zinc, copper and cobalt, the silver concentration being a minor amount, in terms of molar ratio, of the total amount of said platable metal, said electrically conductive backing being connected as cathode.

2. The process of producing a long-lasting visible reproduction of a graphic original on strongly photoconductive zinc oxide coated copy-paper having a photoconductive coating on an electrically conductive backing, said copy-paper being capable of electrolytic image reproduction thereon, comprising exposing the coated surface to a light image corresponding to said graphic original and electrolyzing at the conductive light struck areas a liquid developer solution consisting essentially of, in solution in an

ionizing solvent, from about 0.1 to about 5 weight percent of a silver salt and from about 1 to about 15 weight percent of a soluble salt of a platable metal selected from the group consisting of cadmium, nickel, zinc, copper, and cobalt, the silver concentration being a minor amount, in terms of molar ratio, of the total amount of said platable metal, said electrically conductive backing being connected as cathode.

3. The process of claim 1 in which the platable metal is cadmium.
4. The process of claim 1 in which the platable metal is nickel.
5. The process of claim 1 in which the platable metal is zinc.
6. The process of claim 1 in which the platable metal is copper.
7. The process of claim 1 in which the platable metal is cobalt.
8. The process of claim 2 in which the platable metal is cadmium.
9. The process of claim 2 in which the platable metal is nickel.
10. The process of claim 2 in which the platable metal is zinc.
11. The process of claim 2 in which the platable metal is copper.
12. The process of claim 2 in which the platable metal is cobalt.
